UNITED STATES PATENT OFFICE.

POVL T. LINDHARD, OF NEW YORK, N. Y., ASSIGNOR TO F. L. SMIDTH & CO., OF NEW YORK, N. Y., A CORPORATION OF NEW JERSEY.

TUBE-MILL.

983,069.

Specification of Letters Patent. Patented Jan. 31, 1911.

Application filed January 5, 1910. Serial No. 536,448.

To all whom it may concern:

Be it known that I, POVL T. LINDHARD, a subject of the King of Denmark, residing in the borough of Manhattan of the city of New York, in the State of New York, have invented certain new and useful Improvements in Tube-Mills, of which the following is a specification, reference being had to the accompanying drawing, forming a part hereof.

This invention relates to rotary mills in which coal or any other substance to be pulverized is first subjected to the action of relatively large grinding bodies and then passed through a perforated partition into another compartment in which the partly pulverized material is subjected to the action of small cylindrical grinding bodies. In order that the openings through the partition shall not become clogged by the partly pulverized material, such openings are made to flare toward the second compartment and, being usually formed as long slots in the partition, so that ample space may be afforded for the passage of the partly pulverized material, it is found that the small, cylindrical grinding bodies used in the second compartment, having a diameter less than the maximum width of the slots, sometimes lodge in the slots with their axes parallel with the plane of the partition, thereby clogging the openings and restricting the free passage of the partly pulverized material therethrough.

It is the object of this invention to so form the openings through the partition that the small cylindrical grinding bodies cannot lodge in such openings with their axes parallel with the plane of the partition and wherein each slot through the partition, although having a total continuous length many times the length of a small, cylindrical grinding body and flaring toward the second compartment so as to permit clearance of the partly pulverized material, is formed with bearing points separated by less than the length of a grinding body, so that the grinding bodies cannot lodge in the slots with their axes parallel with the plane of the partition. They may lodge with one end in the slot and the other projecting into the compartment, but if they do so lodge they will be dislodged quickly by the striking of the projecting ends by other grinding bodies

in the second compartment. It will be obvious that the slots may be formed in many different ways in order to secure the desired result and in the drawing several different forms are illustrated.

In the drawing—Figure 1 is a view in longitudinal section of a tube-mill which embodies the invention. Fig. 2 is a detail view, on a larger scale, of the partition as seen from the right hand in Fig. 1. Fig. 3 is a detail view in section on the plane indicated by the line 3—3 of Fig. 2. Figs. 4, 5 and 6 are detail views showing different forms which may be given to the slots in accordance with the invention.

The tubemill may be constructed in any suitable manner. As shown in Fig. 1 of the drawing, it comprises the usual cylindrical shell *a* with a feed head *b* and a discharge head *c*. Usually such a mill has but a single grinding chamber, in which are placed the grinding bodies which are usually comparatively large flint pebbles. It has been found, however, that much better results can be secured if the material to be pulverized is first subjected to the action of the flint pebbles, indicated at *d*, in a relatively large compartment *e*, and the partly pulverized material passes immediately from the compartment *e*, through a perforated partition *f*, into a smaller compartment *g*, in which it is subjected to the action of comparatively small, cylindrical grinding bodies *h* of metal, the pulverized material finally passing out of the shell *a* through the discharge head *c*. In order that the partly pulverized material may pass freely from the compartment *e* to the compartment *g*, it has been found desirable to form in the partition *f* numerous long slots which flare outwardly toward the compartment *g*. It has also been found, however, that if the slots are simple straight slots, exceeding in length the length of the grinding bodies *h*, it frequently happens that the grinding bodies *h*, the diameter of which is less than the maximum width of the slots, lodge in the slots with their parallel axes with the plane of the plate, thereby, to that extent, clogging the slots and preventing the free passage of the partly pulverized material.

In accordance with this invention, the slots *f'* in the partition plate *f* have each a length considerably greater than the length

of a grinding body and are flared toward the compartment g , but each continuous long slot is formed with bearing points which are separated by a distance less than the length of one of the grinding bodies h , so that a grinding body cannot lodge in a slot with its axis parallel with the plane of the plate, but if it lodges in the slot at one end, shall have its other end beyond the face of the plate so that it shall be struck by other grinding bodies in the compartment g and shall be dislodged. It will be obvious that the slots may be so formed as to provide the necessary bearing points in many different ways. Preferably each slot is zigzag, either on straight lines, as shown in Figs. 2 and 5, or on straight lines as shown at f' in Fig. 3, and at f'' in Fig. 5, or on curved lines as shown at f^3 in Fig. 6. If the continuous slot f' is formed, as shown in Figs. 2 and 3, of short staggered sections, the points f^5 form bearing points which are separated longitudinally by a distance less than the length of a grinding body h , and are separated laterally by a distance less than the diameter of such grinding body, so that it is impossible for a grinding body to lodge in the slot with its axis parallel with the plane of the plate, while neither the effective area of the slot nor the flaring necessary to give clearance is reduced. If the slot be zigzag with straight lines, as shown at f^3 in Fig. 5, or with curved lines, as shown at f^4 in Fig. 6, bearing points are formed at f^6 , f^7 and f^8 in Fig. 5 and at f^9 and f^{10} in Fig. 6, which are separated by less than the length of a grinding body h so that it is impossible for such grinding body to lie in the slot with its axis parallel with the plane of the plate. Preferably, each slot, although continuous, is zigzag, in one way or another, as indicated in Figs. 2, 5 and 6, so as to have no straight part of such length and width as to be capable of receiving one of the grinding bodies h , the chamfering off of the side of each slot to give the necessary flare being continuous, but the same result may be secured, as shown at f^2 in Fig. 4, by making the slot straight and by chamfering off the sides of the slot in saw-tooth notches f^{11} , the points f^{12} being separated longitudinally by a distance less than the length of a grinding body and laterally by a distance less than the diameter of a grinding body. Various other modifications of the form of the slots will readily suggest themselves in view of the foregoing and it is obvious

that the invention is not limited to any particular form.

The invention has been thus far described with relation to the mid-partition or transverse wall f between the two compartments but as the end partition or transverse wall of the discharge head c may also be formed with slots which flare toward the discharge end of the tubemill, such slots of such end wall may also be formed as described with reference to the mid wall f and as shown in Figs. 2-6. The liability of the grinding bodies to lodge in the slots of the end wall, which flare away from the compartment, is much less than in the case of the slots in the mid-wall, which flare toward the compartment, but should such lodging occur the formation of the slots described will insure the endwise portion of the grinding bodies from which they are likely to be dislodged by the grinding bodies within the compartment.

I claim as my invention:

1. The combination with a tubemill and relatively small, cylindrical grinding bodies of a transverse wall having continuous slots longer than the cylindrical grinding bodies and formed with bearing points separated by less than the length of a grinding body, whereby a grinding body cannot lodge in the slot with its axis parallel with the plane of the wall.

2. The combination with a tubemill and relatively small, cylindrical grinding bodies of a transverse wall having continuous slots longer than the cylindrical grinding bodies and flaring toward the discharge end of the tubemill and formed with bearing points separated by less than the length of a grinding body, whereby a grinding body cannot lodge in the slot with its axis parallel with the plane of the wall.

3. The combination with a tubemill and relatively small, cylindrical grinding bodies of a transverse wall having zigzag continuous slots forming bearing points separated by less than the length of a cylindrical body, whereby a grinding body cannot lodge in the slot with its axis parallel with the plane of the wall.

This specification signed and witnessed this 3rd day of January, A. D. 1910.

POVL T. LINDHARD.
